UNITED STATES PATENT OFFICE

JOHN O. ALMEN, OF ROYAL OAK, MICHIGAN, ASSIGNOR TO GENERAL MOTORS RESEARCH CORPORATION, OF DETROIT, MICHIGAN, A CORPORATION OF DELAWARE

HYDRAULIC BOOSTER MECHANISM

Application filed December 31, 1928. Serial No. 329,621.

This invention relates to a steering mechanism and has been designed more particularly for the actuation by power of the steering wheels of vehicles. Its use in other relations will, nevertheless, be obvious.

An object of the invention is to provide fluid pressure means to effect the steering. As a further object, the invention aims to so relate the conventional steering wheel to the novel fluid pressure means that the rotation of the steering wheel may render the fluid pressure means active. Another object is to so arrange the mechanism that the power means shall continue active only so long as the steering wheel is being turned. Other objects such as efficiency, and simplicity in construction, will be understood from a reading of the following description.

In the drawings accompanying this description:

Figure 1 is a side elevation of the novel mechanism associated with a side frame member of the vehicle chassis.

Figure 2 is a longitudinal section through the power cylinder.

Referring by reference characters to the drawings, numeral 3 is the usual steering wheel carried by a steering post 5. This steering post 5 is rotatably mounted in a bracket 7 securely fastened as by fastening means at 9. The post 5 is provided with a worm 13 engaging the teeth of a sector 15 rotatably mounted about a rock shaft 17 journalled in the bracket. At an opposite end of the bracket there is journalled a rock shaft 19 having arms 21 and 23 secured thereto. Secured to shaft 17 is an arm 25 and a link 27 connects arms 21 and 25. The sector 15 extends below the shaft 17 having the form of a downwardly directed arm 29. Between arm 29 and arm 23 is mounted the fluid pressure cylinder 31, the cylinder being connected to the bracket by fastening means 33. A tubular piston rod 34 projects through the integral head 35 of the cylinder 31 and is connected to arm 23. A tubular valve rod 36 projects through the removable head 37 attached to the cylinder by fastening means 39 and is connected to arm 29. The sector is provided with stops 41 projecting in spaced

relation to the sides of arm 25 so that at times the freely rotatable sector may be rendered immovable relative to arm 25, and thereby may function to rotate the arm 25 and shaft 17 manually. For connection with the conventional steering elements, the shaft 17 has an arm 43 to be connected by the drag link with the wheel in a manner well understood, but not illustrated.

The power cylinder 31 contains a hollow piston, represented by numeral 45. This piston is formed by a barrel 47 with end flanges 49 and 51. Flange 51 is tapered to form a valve seat 53 and is provided with an axial opening 55. Fastening means 57 serve to secure to flange 51 a piston head or closure 59. This closure has a recess 61 and a conduit 63 registering with opening 55. The conduit extends toward the removable head 37 and terminates in an axial bore 65 provided in the stem portion of the piston closure. This extended end of the piston head or closure passes through the removable head 37 and surrounds the valve rod 36 mentioned above. The closure also has an opening 60 affording communication between the recess 61 and the adjacent end of the cylinder. At the other end of the piston there is an annular valve seat 67 and a closure head 69 the seat 67 and the head 69 being held in place by bolts 70. The closure 69 is formed with a recess 71 and with an opening 73 affording communication between recess 71 and the end of the cylinder. Beyond the recessed portion of the head, it is reduced in diameter to form the hollow piston rod 34 referred to above, which piston rod extends through the cylinder head 35 and is connected to arm 23. Within the hollow piston there are opposed valves 75 and 77. These valves are seated against valve seats 67 and 53. They are normally held so seated by a common spring 79. These valves are provided with angularly related faces as shown to engage the valve seats and, also, to engage other valve members as explained below. The valves are also provided with recesses 80 for a purpose to be described.

The valve rod 36 is tubular at each end, but between the tubular ends it is solid as shown

at 82. At the end of the valve rod adjacent the removable head 37, it has an opening 81 of sufficient dimensions to at all times register with conduit 63. At its outer end the tubular 5 valve rod has a threaded stem 83 for the attachment of a pipe to be connected to the high pressure side of a fluid pressure pump. At the other side of the intermediate closure 82, the other tubular part is in communication 10 by means of openings 87 with the recesses 80 of the valves. The valve rod has secured thereto, or integral therewith, valves 89 and 91. The valves 89 and 91 are so spaced that when the valves 75 and 77 engage their seats 15 carried by the piston they also engage the valves carried by the valve rod, as well shown by Figure 2. The valve rod is arranged to reciprocate through the tubular portions of both piston end closures. It terminates short of 20 the outer attached end of the piston rod 34. The tubular opening of the piston rod 34 is in free communication with the tubular valve rod as shown in the drawings. The piston rod 34 has also a threaded stem 95 for the 25 attachment of a pipe to be connected to the low pressure side of the pump. Since the pump does not constitute a part of the invention, and since any fluid pressure pump may be used, it has not been thought necessary to illustrate such a pump in connection 30 with the invention.

The operation of the device is as follows: The drawings show the parts at rest, as when the vehicle is moving straight ahead. 35 When it is desired to turn, for the purpose of steering the hand wheel 3 is rotated as usual. In so turning the wheel the worm 13 rotates the freely mounted sector and its arm 29. The arm 29 moves the valve rod 36 either 40 inwardly or outwardly, depending upon the direction of rotation of wheel 3. If the rotation is such as to thrust the valve rod inwardly, the valve 89 pushes valve 77 off its seat. Fluid under pressure from the pump 45 is then free to flow into opening 83, through the hollow valve rod, through conduit 63 into the hollow piston 45, out between valve 77 and its seat 53, through the recess 61 and out through opening 60 into the adjacent cylinder end. This pressure is then effective to 50 move the piston to the left (Figure 2). At the same time, valve member 91 has been moved to the left of the valve 75, which continues to seat on valve seat 67. Fluid in the 55 adjacent end of the cylinder may then pass through opening 73, recess 71, between valve 91 and valve 75 into recess 80 and through opening 87 out through the tubular end of the valve rod and the piston rod, returning 60 to the pump by passage 95. No resistance is, therefore, offered to the movement of the piston to the left. The movement of the piston is transmitted by the rod 34, arms 23 and 21, link 27 and arm 25 to rock shaft 17, 65 the rotation of which serves to steer the ve-

hicle in an obvious manner. If the rotation of wheel 3 is stopped, the valve rod 36 also ceases to move and the pressure of the fluid in moving the cylinder at once effects the closing of the valve 77 against its seat 53, and the parts are restored to their original position. The vehicle may be further steered by further movement of wheel 3.

Should it be desired to steer in the reverse direction, valve rod 36 is drawn outwardly 75 and the valve 91 lifts valve 75 off its seat, affording free passage for the fluid under pressure from within the piston to the left end of the cylinder. At the same time, the pressure at the right of the piston is relieved by the opening of the valve 89 from its seat on valve 77. The fluid at the right of the cylinder escapes from recess 80 through opening 87 and out through the power piston rod as 80 before.

In the event that the fluid pressure means fails, the movement of the sector is effective to apply the steering gear by manual effort solely through the engagement of stops 41 with the arm 25.

I claim:

1. A fluid pressure device comprising a cylinder, a hollow piston having opposed valve seats, means to conduct fluid under pressure to the space within said piston and between said valve seats, said piston being reciprocable within said cylinder, a piston rod connected to said piston and projected through one end of the cylinder, connections from said rod whereby movement of said piston may perform work, a valve rod reciprocable through the opposite end of said cylinder and also reciprocable through said piston, valves rigid with said rod, valves within said piston and seating against said rod valves and movable thereby, and also seated against the piston valve seats, yielding means between said last-named valves, whereby reciprocation of said valve rod in either direction opens a valve to permit the fluid under pressure to pass from within the piston to one end of the cylinder and whereby said movement opens another valve to permit the relief of pressure in the other end of the cylinder.

2. In combination, a cylinder with closed ends, a hollow piston reciprocable therein, a tubular piston rod rigid with the piston and reciprocable through one end of the cylinders, connections from said rod whereby movement of said piston may perform work, a valve rod having tubular ends and an intermediate solid portion, said valve rod being reciprocable through the other end of the cylinder, through the hollow piston and slidably guided within the piston rod, connections whereby the tubular portions of the valve rod may be connected respectively to a high pressure and a low pressure side of a source of fluid pressure, means comprising a conduit whereby the high pressure tube of 120 125 130

the valve rod is in communication with the interior of the hollow piston, opposed valves in said pistons, said valves surrounding and capable of movement by said valve rod to admit fluid pressure from within said piston to one of the cylinder ends and to simultaneously permit the escape of fluid pressure from the other side.

connections operable upon said valve mechanism whereby the power operated mechanism rotates said fixed lever on the second shaft and, through the instrumentality of the link-connecting means, rotates the first shaft and actuates the work-performing means.

In testimony whereof I affix my signature.

JOHN O. ALMEN.

3. In a power operating mechanism, a rock shaft, an arm rigid therewith for performing work, a second arm rigid with said shaft, a parallel shaft, oppositely directed arms on said parallel shaft, a link connecting the second arm of the first shaft with one of the arms of the parallel shaft, a power cylinder fixed in position, a piston in said cylinder, a piston rod extending therefrom and connected to the other arm of the parallel shaft, a valve rod reciprocable in said power cylinder to render said power cylinder operable upon the rock shaft in either direction of reciprocation, a sector rotatable on said rock shaft, manually operable means operably connected to rotate said sector, and a connection from said sector to said valve rod whereby the actuation of said manually operable means renders the power cylinder operative in either direction of rotation of said manually operable means.

4. Power operating mechanism comprising parallel shafts, a rigid arm on the first one of said shafts, means whereby rotation of said first shaft performs work, a lever rotatably mounted on said first shaft, manually operable means to rotate said lever, a lever fixed to said second shaft, link connection between said fixed lever and the fixed arm on the first shaft whereby the rotation of the second shaft rotates the first shaft, power operated mechanism, connections therefrom to both said fixed lever and said rotatable lever, valve mechanism associated with said power operated mechanism, one of said connections operable upon said valve mechanism whereby the power operated mechanism rotates said fixed lever.

5. The invention defined by claim 4, together with means to limit the rotary movement of said manually operable means relative to said first mentioned shaft.

50 6. Power mechanism comprising parallel shafts, a rigid arm mounted on a first one of said shafts, means whereby rotation of said first shaft may perform work, a lever rotatably mounted on said first shaft, manually operable means to rotate said last-mentioned lever, a lever fixed to the second shaft, link-connecting means between an arm of the lever fixed to the second shaft and the rigid arm on the first shaft whereby rotation of the second shaft rotates the first shaft, power operated mechanism, connections therefrom to a second arm of the lever fixed to the second shaft and to the rotatable lever on the first shaft, valve mechanism associated with said power operated mechanism, one of said
